DESIGN FOR A HAIRBRUSH

Fred Hermann Lotters, Albany, N. Y., assignor to Mohawk Brush Company, Albany, N. Y., a corporation of New York

Application December 16, 1941, Serial No. 104,661

Term of patent 14 years

(Cl. D86—10)

To all whom it may concern:

Be it known that I, Fred Hermann Lotters, a citizen of the United States residing at Albany, in the county of Albany and State of New York, have invented a new, original, and ornamental Design for Hairbrush, of which the following is a specification, reference being had to the accompanying drawing, forming part thereof.

Figure 4 is an end elevational view thereof. The dominant features of my design are shown in solid lines on the drawing and comprise the longitudinal twisted shape of a longitudinally grooved backed brush head having a plurality of longitudinal rows of bristle tufts radiating from a longitudinal axis which is outside the mass of the brush head, as shown.

I claim:

The ornamental design for a hairbrush, as shown and described.

FRED HERMANN LOTTERS.
